DIP CO-ORDINATOR

Walter T. Knauth and Robert B. Briggs,
Houston, Tex.

Application February 24, 1948, Serial No. 10,288

9 Claims. (Cl. 33—76)

1

This invention relates to a dip co-ordinator.

An object of the invention is to provide a plotting instrument specially designed to plot reflection planes from reflection shooting data showing said planes in two dimensional space and in their proper position with respect to the surface line, the point at which the shot occurs and the geophone arrangement (commonly known as geophone spread) with respect to the shot point.

The instrument is also useful in plotting the dip of the planes either in degrees or feet as well as to indicate the vertical depth of the center strike of the planes.

It is common practice to obtain data concerning earth formation beneath the surface by causing an explosion at a selected point, commonly known as the "shot point," and about which geophones have been arranged, and then collecting and correlating the data, registered by the geophones, and resulting from the vibrations caused by the explosion. The instrument herein described has been specially designed to simplify the reduction of said data to practical form and use.

Other objects and advantages will be apparent from the following specification which is illustrated by the accompanying drawings, wherein:

Figure 1 is a plan view of the instrument.

Figure 2 is a plan view of the base plates viewed as indicated by the line 2—2 of Figure 3.

Figure 3 is a front elevation, partly in section, taken on the line 3—3 of Figure 1.

Figure 4 is a fragmentary, side elevation.

Figure 5 is a vertical, sectional view taken on the line 5—5 of Figure 3.

Figure 6 is an end view as indicated by the line 6—6 of Figure 4.

Figure 7 is a fragmentary, side view as indicated by the line 7—7 in Figure 1, and

Figure 8 is a diagram illustrating the use of the instrument.

Referring now more particularly to the drawings, wherein like numerals of reference designate similar parts in each of the figures, the numerals 1 and 2 designate end supporting plates the former of which is, preferably, relatively narrow and extends fore and aft and the latter of which is approximately triangular with its inner apex terminating in a pointer 3 which, in using the instrument, will usually be located at the shot point shown on the reflection plane to be plotted.

Upstanding from these plates are the respective anchors 4 and 5 to which the corresponding

2

ends of the track 6 are fixed. In the present illustration this track is shown as being cylindrical in shape.

Mounted in suitable bearings in these respective anchors 4 and 5 and having swivelling connections therewith and, in the present illustration, above the track 6 there is an externally threaded shaft 7, one end of which extends beyond the anchor 4. Fixed on this extended end there is a thumb knob 8 by means of which the shaft may be turned.

Slidably mounted on the track 6 there is a sleeve 9 upstanding from the inner end of which there is a guide 10 through which the shaft 7 passes loosely. Upstanding from the other end of the sleeve 9 there is a bearing member 11 through which the shaft 7 is threaded.

There are the opposed, similar, protractors 12 and 13 which are fixed on suitable plates 14 and 15. The plate 14 is fastened on the guide 10 and bearing member 11 and the plate 15 is fastened on the anchor 5.

These protractor supporting plates have the forwardly extended, inwardly converging, arms 16 and 17, respectively and pivotally mounted on the free ends of these respective arms are the pointers 18 and 19 whose free ends co-operate with the corresponding protractor scales. The pointers 18 and 19 are pivoted at the centers of the corresponding protractor scale circles, which centers are in a line parallel with the shaft 7.

Extending forwardly from the pivoted ends of the respective pointers 18 and 19 there are the arms 20 and 21 the former of which is slightly longer than the latter.

Fastened to the guide 10 and extending forwardly and inwardly there is a pointer 22, and above it and anchored to said guide 10 there is a forwardly and inwardly extended arm 23. A clevis 24 has its upper end connected to the free end of the arm 20 and the lower end of the clevis is connected to the free end of the arm 23 by means of a link 25.

The clevis 24 forms a connection for one end of the flexible measuring tape 26. This tape passes also through a narrow vertical slit in the guide 27, which depends from the free end of the arm 21, and thence passes between the guide rollers 28, 29 and around the idler roller 29 and thence behind the vertical wave-travel indicator 15a, depending from plate 15, and is spooled onto the spool 30. The rollers 28 and 29 are mounted to rotate between the upper arm 17 and an aligned, similarly shaped lower arm 31 which is fixed to the anchor 5.

The spool 30 is mounted on a sleeve 32 to rotate therewith and the outer end of this sleeve is formed with an integral grip member 33 whereby the sleeve and spool may be turned. The sleeve 32 surrounds, and is mounted on, a post 34 which is anchored to and upstands from plate 2. This post is tubular and internally threaded and its upper end is longitudinally slotted forming expansible friction jaws 34a. These jaws are tapered outwardly, internally, and a tapering expander 35 is fitted between said jaws and its inner end is threaded into the post 34. Its upper end extends above said post and is formed with an integral head 36 forming a grip member whereby it may be turned to control the expansion of said jaws and their frictional engagement with the sleeve 32. In other words the spool is provided with a friction clutch whereby its rotation about post 34 may be controlled.

Slidably mounted on the track 6 between the protractors there is a sleeve 37.

Upstanding from this sleeve there is an anchor 37a through which the shaft 7 is threaded.

Extending forwardly from the upper end of the anchor 37a there is an arm 37b and mounted on the forward end of this arm there is a bearing 38 in which the rod 39 is slidably mounted.

The forward end of this rod is secured to the upper end of an inverted U-shaped bracket 40 having the side legs 41, 41 and secured to and extending forwardly from these side legs 41 there is a supporting arm 42. Depending from the forward end of this arm 42 there is a semi-cylindrical shield 43 in which an idler roller 44 is mounted to rotate on a vertical axis and the measuring tape 26 is looped around said roller 44, passing through the space between the legs 41 and between the opposing vertical rollers 45, 45 which depend from the forwardly extended arm 42.

The lower ends of the legs 41 are anchored to a transversely oblong base 46 whose forward margin is formed into a straight edge 47 which is in vertical alignment with the rollers 45.

Mounted on the bearing 38 there is a suitable tensioning device 49 of any selected construction and a flexible wire 50 is attached, at one end, to the rear end of the rod 39 and its other end is connected to the tensioning mechanism of said tensioning device whereby the roller at the forward end of the rod 39 will hold the measuring tape looped therearound under tension.

The threads of the shaft 7 through the bearing member 11 have twice the pitch of the threads of said shaft through the anchor 37a so that, as the shaft 7 is turned, the rack members 12 and 13 will be maintained spaced the same distance on opposite sides of the pivot point of shaft 39.

To illustrate a use of the instrument and assuming a shot is fired at or just under the surface of the earth and a seismic reflection recorded on five geophones placed on said surface equal distances, of five hundred feet, apart in a straight line extending westward and with the nearest geophone located one thousand feet from said shot point 51, Figure 8. As illustrated graphically in Figure 8, on a scale in which one inch equals one thousand feet, this east-west line is indicated by EW and represents the surface of the earth, and the geophones are indicated by the numerals 1', 2', 3', 4' and 5'.

The above arrangement may be laid out graphically and the instrument may be placed on the

graph with the forward margins, or straight edges, of the supporting plates 1 and 2 along the line EW of the graph with the pointer 3 at the shot point 51. The instrument should be firmly secured in this position. This may be done in any preferred manner, as by thumb tacks through the holes, as 52, in the supporting plates 1, and 2. The pointer 22 should be moved by rotation of shaft 7 to the center of the geophone spread, that is to the indicated geophone 3'.

Assuming, now, that the seismic reflection was recorded on geophone 3' in two and five tenths (2.5) seconds after the shot was fired and that the seismic wave generated by the shot travelled at an average speed of seven thousand feet per second and overall travel of this wave was fourteen thousand three hundred and fifty feet. The reflection planes are indicated on the graph by the numerals 1'', 2'', 3'', 4'' and 5''.

This overall wave travel of fourteen thousand three hundred and fifty feet may now be established on the instrument by rotating spool 30 until the wave travel indicator 15a corresponds to fourteen thousand three hundred and fifty feet on tape 26 and the tape locked in this position by the jaws 34a. In this position of the tape 26 the scale is so arranged that the total distance from pointer 3, corresponding to the shot point, to the mid-point between rollers 45, which corresponds to reflection plane 3'', and back to the pointer 22, which corresponds to the center of geophone spread 3', remains constant at 14.35 inches while the straight edge 47, corresponding to the line 5'', 1'' on the graph may be oscillated for the final instrument setting.

Assuming now that the record also showed that the geophone 1' received a seismic reflection .079 of a second later than geophone 5' it would mean that the wave travel from shot point 51 to reflection plane 1'' and back to geophone 1', calculated at seven thousand feet per second, would be five hundred and fifty three feet further than the wave travel from shot point 51 to reflection plane 5'' and back to geophone 5'. Thus, there is graphically formed the angle 53, 5', 1' whose trigonometric sin is distance 53 to 1' (553 feet) divided by distance 5', 1' (2000 feet) or numerically .275. Thus the angle 53, 5', 1' is established as sixteen degrees which corresponds to the angle whose sin is .275.

The straight edge 47 may now be moved until the pointer 18 reads 16 degrees on the negative portion of the protractor scale 12. This angle setting illustrated on the graph corresponds to the angle 54, 3', 5', which equals the calculated angle 53, 5', 1'.

Since in the above example geophone 5' received the reflected wave earlier and not later than the geophone 1' the stepout time, that is the time delay in reflection arrival to geophone 5' over that of geophone 1' a negative stepout time was thereby indicated; consequently, the calculated angle of 16 degrees was in reality a negative angle and the pointer 18 was therefore moved upward on the negative portion of the scale. When the instrument is in this position the profile of the reflection plane may be drawn along the straight edge as 5'', 1'' on the graph. For all practical purposes the length of the profile plane may be half of the geophone spread or one inch on the graph, but should be equal distance to right and left from the vertical line where the tape 26 passes through between the rollers 45.

Since seismic reflections follow the law governing reflections namely, the angle of incidence

equals the angle of reflection, it is essential in order to approximate this relation within limits that straight edge 47 remain perpendicular to a line from its center to a point on the line through, and midway between, pointers 3 and 22. The straight edge 47, therefore, is mounted perpendicular to the rod 39 and the rod 39 extends through the bearing block 38 which remains pivoted in vertical alignment with, and half way between, pointers 3 and 22 for all positions of pointer 22. This results from having the threaded portion of shaft 7 which moves sleeve 37 threaded to half the pitch of that portion of the shaft threaded through the bearing member 11.

The drawings and description illustrate and describe what is now considered to be a preferred form of the invention, however, by way of illustration only while the broad principle of the invention will be defined by the appended claims.

What we claim is:

1. An instrument of the character described comprising, supporting means having a fixed and a slidable pointer thereon, a transverse track on the supporting means, a shaft aligned with the track, protractors, one fixed to the supporting means and a protractor support slidable on the track with which the shaft has a threaded connection and on which the outer protractor is mounted, pointers pivotally mounted with respect to, and arranged to co-operate with, said protractors, a tension rod support slidable on the track and through which said shaft is threaded, a forwardly extended tension rod on the support, anti-friction means carried by the forward end of the rod, a flexible measuring tape movable about said anti-friction means and one end of which is connected to one of the pivotal pointers, said tape also having a slidable operative connection with the other pivotal pointer and storage means on which the other end of the tape may be stored.

2. An instrument of the character described comprising, supporting means, a fixed pointer and a movable pointer thereon, a rotatable threaded shaft on the supporting means, protractors, one fixed on the supporting means and a protractor support slidable on the supporting means and with which the shaft has a threaded connection and on which the other protractor is mounted, pointers pivotally mounted with respect to, and arranged to co-operate with, the corresponding protractors, and having extensions, a tension rod support slidable on the supporting means and through which the shaft is threaded, a tension rod slidable on the support, anti-friction means carried by said rod, a flexible measuring tape movable about said anti-friction means and one end of which is attached to one extension, said tape also having an operative slidable connection with the other extension and storage means on which the other end of the tape may be spooled.

3. An instrument of the character described comprising, supporting means, a fixed pointer and a movable pointer thereon, a rotatable threaded shaft on the supporting means, protractors, one fixed on the supporting means and a protractor support slidable on the supporting means and with which the shaft has a threaded connection and on which the other protractor is mounted, pointers pivotally mounted with respect to, and arranged to co-operate with, the corresponding protractors, and having exten-

sions, a tension rod support slidable on the supporting means and through which the shaft is threaded, a tension rod slidable on the support, anti-friction means carried by said rod, a flexible measuring tape movable about said anti-friction means and one end of which is attached to one extension, said tape also having an operative slidable connection with the other extension, storage means on which the other end of the tape may be spooled and resilient means adapted to act against the rod to maintain the runs of the tape under tension.

4. An instrument of the character described comprising, supporting means having a fixed and a slidable pointer thereon, a transverse track on the supporting means, a shaft aligned with the track, protractors, one fixed to the supporting means and a protractor support slidable on the track with which the shaft has a threaded connection and on which the other protractor is mounted, pointers pivotally mounted with respect to, and arranged to co-operate with, said protractors, a tension rod support slidable on the track and through which said shaft is threaded, a forwardly extended tension rod on the support, anti-friction means carried by the forward end of the rod, a flexible measuring tape movable about said anti-friction means and one end of which is connected to one of the pivotal pointers, said tape also having a slidable operative connection with the other pivotal pointer, storage means on which the other end of the tape may be stored and a fixed wave indicator in advance of the storage roll adjacent which the tape passes.

5. An instrument of the character described comprising, supporting means, a fixed pointer and a movable pointer thereon, a rotatable threaded shaft on the supporting means, protractors, one fixed on the supporting means and a protractor support slidable on the supporting means and with which the shaft has a threaded connection and on which the other protractor is mounted, pointers pivotally mounted with respect to, and arranged to co-operate with, the corresponding protractors, and having extensions, a tension rod support slidable on the supporting means and through which the shaft is threaded by means of threads of one half the pitch of the threads connecting the shaft to said support, a tension rod slidable on the support, anti-friction means carried by said rod, a flexible measuring tape movable about said anti-friction means and one end of which is attached to one extension, said tape also having an operative slidable connection with the other extension and storage means on which the other end of the tape may be spooled.

6. An instrument of the character described comprising, supporting means, a fixed pointer and a movable pointer thereon, a rotatable threaded shaft on the supporting means, protractors, one fixed on the supporting means and a protractor support slidable on the supporting means and with which the shaft has a threaded connection and on which the other protractor is mounted, pointers pivotally mounted with respect to, and arranged to co-operate with, the corresponding protractors, and having extensions, a tension rod support slidable on the supporting means and through which the shaft is threaded, a tension rod slidable on the support, a bearing surface carried by said rod, a flexible measuring tape movable about said bearing surface and one end of which is attached to one extension, means

adjacent said bearing surface for holding the runs of the tape closely together, said tape also having an operative slidable connection with the other extension, storage means on which the other end of the tape may be spooled and resilient means adapted to act against the rod to maintain the runs of the tape under tension.

7. An instrument of the character described comprising, supporting means having a straight edge, a fixed and a movable pointer on the supporting means aligned with the straight edge, a rotatable threaded shaft on the supporting means, protractors, one fixed on the supporting means and a protractor support movable along the supporting means and with which the shaft has a threaded connection and on which the other protractor is mounted, pointers pivotally mounted with respect to, and arranged to co-operate with, the corresponding protractors, a tension rod support slideable on the supporting means and with which the shaft has a threaded connection, said support having a bearing mounted to pivot on a vertical axis, a tension rod slideable in said bearing, a straight edge carried by, and at right angles to, said rod, a bearing surface carried by the forward end of said rod, a flexible measuring tape movable about said surface and one of which has connection with one pivotal pointer, said tape also having an operative slidable connection with the other pointer and storage means on which the other end of the tape may be spooled.

8. An instrument for plotting reflection planes from geophysical data said instrument having a straight edge adapted to be positioned to coincide with a base reference line which indicates, graphically, the geophone arrangement with reference to the shot point, point markers one fixed and the other adjustable longitudinally

relative to said straight edge, a graduated tape provided to represent the graphical overall wave travel, a protractor for indicating the graphical angle between the reflected wave and the shot point, a tape guide rod adjustable longitudinally and pivotally mounted midway between the graphical shot point and the graphical center of the geophone spread so that the angle of incidence is substantially equal to the angle of reflection of the graphical wave travel relative to the final graphical plot of reflection plane.

9. An instrument for plotting reflection planes from geophysical data comprising, supporting means having a straight edge, a fixed and a movable pointer on the supporting means and substantially aligned with the straight edge, a tension rod support movable relative to the supporting means, a tension rod mounted to slide longitudinally on, and to pivot on a vertical axis relative to, said support, adjusting means on the supporting means with which said support has an adjustable connection, protractors, one fixed on the supporting means and a protractor support movable along the supporting means and with which the adjusting means has an adjustable connection and on which the other protractor is mounted, pointers pivotally mounted with respect to, and arranged to co-operate with, the corresponding protractors, a straight-edge carried by, and at, substantially, right angles to said rod, a bearing at the forward end of the rod, a flexible measuring tape movable about said bearing and one end of which is connected to one pivotal pointer said tape also having an operative slidable connection with the other pointer.
